BOTTLE CAP AND METHOD FOR MAKING
THE SAMERudolph Sonnenberg Belvidere, Ill., assignor to
Mid-West Bottle Cap Co., Belvidere, Ill., a cor-
poration of Illinois

Application July 1, 1940, Serial No. 343,407

10 Claims. (Cl. 215—38)

This invention relates to bottle caps and more particularly to the type of so-called hood caps used on dairy bottles for the delivery of milk, cream and the like. The invention also relates to a method for making a cap of the type described, and to a hood member adapted to be marketed as such and used in the manufacture of said caps.

Some of the more serious difficulties with the hood caps of the prior art have long been recognized. In the past, the most common type of milk bottle cap has been formed of paper gathered over the mouth and around the neck of the bottle, the mouth of the bottle being closed by a paper disk. It is apparent that the paper, regardless of how well it is treated, tends to soften in the presence of moisture absorbing the water and frequently the objectionable bacteria which have an opportunity to contaminate the milk. The hood, on the other hand, has required relatively strong fastening means to hold the same around the neck of the bottle, and this entails expense in applying the cap, and frequently the wires or other fastening means are difficult to remove. Recent attempts to solve this difficulty have led to the use of metal caps arranged to seat over the mouth of the bottle, but the use of this type of cap has entailed considerable expense because of the cost of metal in producing a hood of sufficient size. A further difficulty has been that many styles of these caps do not conveniently permit of re-capping the bottle in the home after a part of the contents has been removed.

An important object of the invention is the provision of an improved hood cap of such form that very thin metal may be employed in its manufacture, whereby a substantial skirt may be employed on the cap without increasing the cost thereof to a prohibitive extent.

A further object of the invention is the provision of a novel pre-formed cap of thin metal having shape characteristics which permit the stacking of the caps in compact stacks in such manner that the individual caps can be freely withdrawn in succession from the stack for feeding purposes.

A still further object of the invention is the provision of a hood cap formed of a metal hood portion and a disk cap of conventional form and shape, thereby permitting the dairy operator to stock the hoods in quantities and apply selected disks thereto at the time of capping.

A further object of the invention is the provision of a hood cap having a metallic hood of

thin cross-section wherein the hood is formed by folding operations and the excess of metal at the lip of the bottle is gathered into spaced ribs for the purpose of stiffening the hood.

5 A further object of the invention is the provision of a hood member for milk bottles formed of thin section metal wherein the metal is folded to produce a central mouth-spanning portion provided with a depressed center, and an annular skirt portion of novel characteristics facilitating the feeding of the hoods.

10 A still further object of the invention is the provision of a hood member of thin cross-section metal having a central mouth-spanning portion provided with an annular shoulder for centering the hood on the bottle and for guiding a cap disk into seated position on the bottle, the mouth-spanning portion having a depressed center to supply stock to the periphery during the disk seating operation.

15 A still further object of the invention is the provision of a novel method of forming a completed cap, wherein the final steps of the cap forming operation are performed directly on the bottle in a novel manner.

20 Other objects and advantages will appear from the following description and the accompanying drawing, in which—

Figure 1 is a side elevation of a stack of hood members;

25 Fig. 2 is a section through one of the cap hood members;

Fig. 3 is a top view of the hood member;

Fig. 4 is a section on the line 4—4 of Fig. 3;

30 Fig. 5 is a section on the line 5—5 of Fig. 3;

Fig. 6 is a vertical section through the neck of a milk bottle and through a cap, showing one of the steps of forming the completed cap on the bottle;

35 Fig. 7 is a side elevation partly in section showing the completed cap in position on the bottle, and

Fig. 8 is a section through the skirt of the cap taken on the line 8—8 of Fig. 7.

40 The invention contemplates a hood cap for milk bottle and the like comprising basically two parts, one being a conventional disk type cap member designated generally by the numeral 9 (Figs. 6 and 7), and the other being a hood member separately shown in Figs. 2 and 3. These members are fabricated and sold separately to the dairy and are assembled directly on the bottle during the capping operations to produce the completed cap, as shown in Fig. 7. The hood member 11 is formed of thin section sheet metal,

preferably aluminum, though other metal of suitable properties and price may be used.

Referring first to the structure of the hood member, this member is formed from a sheet of aluminum foil which may vary to a substantial extent in thickness, though the greater advantages of the invention accrue when the metal is of a minimum thickness consistent with the production of the desired results. I have found that metal of approximately .0015 operates satisfactorily, and in some types of service I may use metal of substantially lesser thickness, as for example, .001. Likewise, under severe conditions of service I have used metal of .002 and .0025. While heavier section metal may be used, this appears to give sufficient strength and rigidity for substantially all requirements, and no particular advantage is gained by using heavier section metal since the cost of the caps increases with increasing thickness.

It will be understood that foil of such thin section presents difficult handling problems, one difficulty being that of producing the shape characteristics required for a pre-formed hood. The metal can only be drawn to a very limited extent without rupturing the sheet or without reducing the thickness to such a point as to destroy its strength. For this reason the hood member is formed almost entirely by folding and gathering operations.

The hood member consists of a flared skirt designated generally by the numeral 11, an intermediate rim-engaging portion 12, and a depressed central mouth-spanning portion 13. The skirt portion 11 is provided with a uniform succession of completed portions formed by bending sections of the skirt as shown at 14 into a plane substantially at right angles to the adjoining portions of the skirt, these bent portions being substantially in the shape of a V, as will best be seen from Fig. 6, the apex of the V terminating along the margin of the rim portion 12. This causes the periphery of the skirt to be depressed at an angle of about 45°, as will be apparent from Fig. 2, and also produces pleat-like ribs consisting of the sides 14 and sides 15 of substantially greater width than the sides 14. The sides 15 have a substantially uniform curvature along their upper edges where they join the rim portion 12, and along their outer edge as shown at 16 have a considerably greater curvature. This curvature of the surface of the sides 15 and the fact that the sides 14 are of substantially shorter length than the sides 15, are a substantial factor in permitting the caps to be stacked closely one on top of the other, as shown in Figure 1, and yet cause the caps to readily separate one at a time from the stack in cap-feeding operations. This skirt construction is also of importance in rendering the metal of the skirt rigid so that the caps will withstand shipping and handling without substantial distortion of the skirt.

The rim portion 12 is arcuate in cross-section, as best shown in Figs. 2 and 6, and has a plurality of ribs 17 spaced therealong, the number and height thereof being sufficient to gather up the excess stock of the sheet caused by the forming of the rim portion. However, in addition to their function in merely gathering up the excess stock, these ribs also serve to strengthen the rim portion and render the same rigid to facilitate the handling of the hood member. A still further function of these ribs is to cooperate with the disk member 9 to render the completed cap

tamper-proof. In other words, the inner ends of these ribs shown at 18 overhang the central portion of the hood member and when the disk 9 is seated in position, overhang the edge of this disk in such manner that the disk 9 cannot be removed and a new disk re-inserted without mutilating the inner ends of the ribs in such manner that it immediately becomes apparent that the cap has been tampered with. This is an important feature, since modern dairy practice requires that a hood cap in order to be satisfactory, must be such that the cap or the identifying parts thereof cannot be removed and replaced without leaving visible evidence of the tampering.

The central mouth-spanning portion 13 comprises an annular shoulder 19 directly adjacent the rim portion 12 of the hood and a central depressed portion 21 joined to the shoulder 19 by an arcuate wall 22, this arcuate wall serving as a reinforcement of the middle part of the central portion to prevent distortion of the central portion when the upper surface thereof is engaged by a suction cup during feeding operations.

Directing attention now more particularly to Figure 1, it will be seen that the planes of the skirt sections 14 do not pass through the center of the cap. The result of this construction is that when the caps are stacked one upon the other as shown in this figure, the ribs formed by the corners at the junction between the skirt sections 14 and 15 extend helically around the stack, as shown at 23, this resulting from the fact that each cap is offset circumferentially a distance equal to the thickness of the metal from which the cap is made. The purpose of this is to facilitate the successive removal of the hood members from the stack. These feeding operations are conducted by a suction cup designated generally by the numeral 24 which moves into contact with the central part of the hood member. Thereafter the air is exhausted from the center of the suction cup, causing the top cap of the stack to adhere to the cup. During the withdrawal, the cup is rotated slightly so as to move the skirt sections 14 of the top cap away from the corresponding sections of the next lower cap. During this movement it will be seen that the skirt sections 15 act as a cam to urge the cap away from the next succeeding cap, thus causing the caps to break apart at the start of the feeding operation, and preventing the withdrawal of more than a single cap from the stack.

In the last stages of the cap making method, the cap is formed directly on the end of the bottle as shown in Figs. 6 and 7, wherein the numeral 25 designates the neck of a conventional milk bottle having a bead 26, a rim 27, a mouth 28, and a conventional cap seat 29. In Fig. 6 the hood member has been dropped onto the head of the bottle and the disk 9 has been dropped on the upper surface of the hood member in position for the completion of the cap. It will be seen from this view that the arcuate walls 22 of the central mouth-spanning portion and the shoulder 19 facilitate the centering of the hood member over the mouth of the bottle. It will also be seen that the distance diametrically across the mouth-spanning portion 13 above the shoulder 19 is such that the disk member 9 drops freely into place on the shoulder 19. This shoulder is thus a centering means for the disk member 9, and the inner walls of the rim 12

act to guide the disk member into position as shown in Fig. 6.

With the parts in the position shown in Fig. 6 the disk member 9 is urged downward. During the initial part of this movement, the entire hood member is moved down until the rim portion 12 seats in surface contact with the rim 21 of the bottle. Continued movement of the disk member 9 downwardly causes the metal of the rim to be pulled a short distance over the rim of the bottle to tighten the rim portion thereon and to further project the ends of the ribs over the edge of the disk. Further movement causes the metal to be deformed in the junction between the shoulder 19 and the rim portion 12, in effect causing the shoulder to move downward, metal for this movement being drawn from the central portion 21 out against the wall 31 of the bottle mouth until the disk member 9 reaches its seated position shown in Fig. 7. The cap may or may not be caused to move completely to the cap seat, as desired. For this continued movement, the metal may be drawn from the supply in the central portion 21 or the whole cap may be pulled down slightly without producing any substantial drawing of the metal. When the disk member 9 has reached its seated position, the skirt portion 11 is contracted about the bead 26 of the bottle by folding in the skirt sections 14 under the skirt sections 15 in the manner shown in Figs. 7 and 8. This folding in of the skirt may be accomplished in a number of ways, one satisfactory way being by means of a rubber contraction member adapted to force the skirt in against the bead and compress the metal thereagainst. During this contracting operation, any excess metal is drawn up in the form of ribs, as shown at 32, which lend rigidity to the lower end of the skirt.

Attention is directed to the shoulder 19 and the central portion 21, and the functions performed thereby. It will be seen from Fig. 6 that the disk member 9 falls freely onto the shoulder and therefore rests throughout its periphery on this shoulder. The shoulder supports the disk during a start of its downward movement so that the disk member starts into the mouth of the bottle uniformly, the shoulder preventing the disk from tipping and thus pulling a part of the skirt around over the rim of the bottle. At the same time the shoulder acts to center the hood member on the head of the bottle so as to cause the hood to rest in parallel relation with the bottle. The central portion 21 supplies the stock required to permit the disk member to move down to its fully seated position and required to accommodate for variations in the shape and size of the mouths of the bottles. A further function of the shoulder is to provide a uniform resistance around the disk to the downward movement thereof during the seating operation. The arcuate or curved wall 22 serves to rigidify the central portion of the hood member in the hood feeding operations, but also serves, as will be seen from Fig. 6, to facilitate the centering of the hood member on the mouth of the bottle.

Attention is directed to Fig. 7, which shows the manner in which the ribs 18 overlie the disk member 9 and thus serve to retain the disk member in position. These ribs also serve to indicate when the disk member 9 has been removed subsequent to capping. It will be understood that the disk member 9 carries the usual indicia, such as the name of the dairy and the date on which the milk is to be delivered. It may be that un-

scrupulous individuals may desire to remove a disk from bottles of milk undelivered on one day and substitute disks bearing the date of the following day. This is prevented by the ends 18 of the ribs 17, since the substitution of a new disk causes the flattening and distortion of the portion 18 of these ribs so that the cap immediately shows the substitution.

It will be seen that I have provided a partially pre-formed hood cap in which the hood is formed of thin metal foil, and in which the cap making operation is completed directly on the head of the bottle. This structure has numerous advantages, among them being the fact that the disk member 9 may constitute the conventional plug cap. For this reason the dairyman may use the same disk on the hood cap which he is employing for bottles capped in other manners; that is, he may purchase a supply of plug caps, some of which are used for capping bottles in the conventional manner, and others may be used on the hood cap, thus avoiding the necessity of double printing and double stocking of these members. Furthermore, the hood member is purchased separately from the disk, bears no indicia, and consequently may be ordered in large quantities, whereby the dairyman may obtain the benefit of quantity purchases.

I have also provided a pre-formed hood member of such shape that the hoods may be stacked in a substantially shorter distance and in more compact form than prior preformed caps of the same class.

A further advantage of my improved construction is the fact that I may use metal foil of very thin section for the reason that the hood member is so formed as to impart substantial strength thereto against bending, this being accomplished by the folds in the skirt and the ribs 17 and 32. The structure further permits of this use because of the presence of the stiff paper disk 8 seated over the mouth of the bottle which acts to prevent puncture of the metal in the disk spanning portion. In this connection it should be recognized that it is common practice during the delivery of milk to ice the same by covering the case of bottles with chipped ice. The disk 8 protects the thin metal from puncture by the sharp edges of the ice during icing and from accidental puncture during handling. In other words, the required strength across the mouth of the bottle is provided by the disk member 8, whereas the mouth-spanning portion of the hood acts to isolate the paper disk from contact with the contents of the bottle and thus prevent contamination which is alleged to occur because of the swelling of the paper disk and the absorption of polluted water from the exterior.

While I have thus described and illustrated a specific embodiment of the invention, I am aware that numerous alterations and changes may be made within the spirit of the invention, and I do not wish to be limited except as required by the scope of the appended claims, in which

I claim:

1. A pre-formed hood member for milk bottle caps comprising a sheet of thin ductile metal foil shaped to provide a mouth-spanning portion having an annular cap disk-seating shoulder and a depressed central portion receivable into the mouth of a bottle, an annular arcuate rim portion having a wall upstanding from said shoulder, and an annular downwardly flared and pleated skirt, the internal diameter of said wall being slightly greater than the inside diameter of the

mouth of said bottle for free seating of a conventional disk cap on said shoulder, said depressed central portion acting to guide the hood member in the capping position and said shoulder acting to locate the hood member on the bottle, and said wall and shoulder serving to locate a cap disk on the hood member.

2. The combination recited in claim 1 wherein said rim portion is provided with upstanding ribs spaced annularly thereof extending from said skirt portion substantially to said shoulder for stiffening said rim portion and for over hanging said disk member when brought into seated position by insertion of the disk and seating of the cap to prevent replacement of the disk member without detection.

3. A pre-formed hood member for milk bottle caps comprising a sheet of thin ductile metal foil shaped to provide a mouth-spanning portion having an annular cap disk seating shoulder and a depressed central portion receivable into the mouth of a bottle, an annular arcuate rim portion shaped to seat against the rim of a bottle, and an annular downwardly flared pleated skirt portion, said central portion being dished to provide arcuate walls joining said shoulder, said walls acting to strengthen said depressed portion to withstand the feeding action of a suction cup engaged thereagainst in feeding, and acting to center the hood member across the mouth of a bottle during capping operations.

4. A pre-formed hood member for milk bottle caps comprising a sheet of thin ductile metal foil shaped to provide a central depressed mouth-spanning portion, a concentric rim portion, and a concentric annular flared skirt portion having annularly spaced pleats, each of said pleats including an inverted V-shaped section having the point thereof adjacent said rim portion, said section being at about right angles with respect to adjacent portions of the skirt and extending diagonally across the skirt, each of said sections facing in the same direction, said skirt also including portions intermediate said sections curved to present cam surfaces, whereby when said hood members are nested together said sections prevent relative rotation of the hood members in one direction and the intermediate portions cam successive hood members apart upon relative rotation in the opposite direction, the inner edges of said sections acting with said central depressed portion against the bead of a bottle to guide the hood member into centered position.

5. A pre-formed hood member for milk bottle caps comprising a sheet of thin ductile metal foil shaped to provide a central mouth-spanning portion having an annular shoulder and a depressed central portion connected thereto by an arcuate draw in the metal, an annular arcuate rim portion having a wall upstanding from said shoulder, and a bottle rim-engaging area, and a flared annular skirt portion, said rim-engaging area having a plurality of ribs extending transversely thereof to absorb the excess metal occasioned by formation of the rim, and said skirt having annularly spaced pleats to absorb the excess metal occasioned by formation of the skirt and to provide a succession of folds in the completed cap to enclose the bead of a milk bottle and retain the cap thereon, said folds comprising relatively narrow inverted V-shaped sections at about right angles with respect to the adjacent portions of the skirt, the planes thereof being at an angle with respect to the center-line of the member to produce fold lines in a plane through

the axis of the bottle when the folds are closed around the bead thereof, all of said pleats facing in the same direction, whereby when said hood members are nested together said pleats prevent relative rotation of the hood members in one direction and the portions of the skirt between said pleats cams successive hood members apart upon relative rotation in the opposite direction.

6. The method of making a hood cap for milk bottles which comprises forming a hood member of thin sheet metal foil having a mouth-spanning portion including an annular cap disk seating shoulder and a depressed central portion receivable into the mouth of a bottle, a concentric rim portion and concentrically downwardly flared pleated skirt portion, seating said hood member loosely on the head of a bottle, dropping a cap disk onto said shoulder of such size as to firmly engage the interior of the bottle mouth, forcing said cap disk down into the mouth of the bottle to move the hood member downward and seat the rim portion against the rim of the bottle, and to thereafter move the disk with respect to the hood member to pull metal from said depressed portion and iron the metal at said shoulder against the inner wall of the bottle, and thereafter compressing said skirt portion around the bead of the bottle.

7. The method of making a hood cap for milk bottles which comprises forming a hood member of thin sheet metal foil having a mouth-spanning portion including an annular cap disk seating shoulder and a depressed central portion receivable into the mouth of a bottle, a concentric rim portion having a wall flaring upwardly and outwardly from said shoulder and bottle rim-engaging area, said wall and area having transverse ribs spaced circumferentially thereof and an annular downwardly flared pleated skirt portion, seating said hood member loosely on the head of a bottle, dropping a cap disk onto said shoulder of a size to firmly engage the interior of a bottle mouth, forcing said cap disk into the mouth of the bottle to move the hood member downward to seat the rim portion against the rim of the bottle and to draw the rim inwardly to straighten said wall and project said ribs over the periphery of said cap disk and to thereafter move the disk with respect to the hood member to pull metal from said depressed portion and iron the metal at said shoulder against the inner wall of the bottle, and thereafter compressing said skirt portion around the bead of the bottle.

8. A preformed hood member for milk bottle caps comprising a piece of thin sheet metal shaped to provide a depressed mouth-spanning portion receivable in the mouth of a bottle, an annular arcuate rim receiving portion joining said mouth-spanning portion, and an annular downwardly and outwardly flared skirt having annularly spaced open pleats disposed angularly with respect to adjoining portions of the skirt to provide edge contact with the mouth of a bottle when the hood is disposed thereon in an eccentric position, the internal diameter of the upper part of said mouth-spanning portion being slightly greater than the inside diameter of the mouth of said bottle for free reception and seating of a conventional disk cap therein to locate said disk with respect to the hood member, the inner edges of said open pleats being spaced outwardly from said mouth-spanning portion and at an acute angle with respect to said annular rim receiving portion for the free reception of the bead of a milk bottle therebetween to guide the hood

member along the inner edges of said pleats under the weight of the hood member into located position on the bottle when dropped thereon, and being adapted for subsequent closing around the bead of a bottle.

9. A preformed hood member for milk bottle caps comprising a piece of thin sheet material shaped to provide a mouth-spanning portion having an annular cap disk seating shoulder and a depressed central portion depending from the inner edge thereof receivable in the mouth of a bottle, an annular arcuate rim receiving portion having a wall upstanding from said shoulder and an annular downwardly and outwardly flared skirt having annularly spaced open pleats, the internal diameter of said wall being greater than the internal diameter of the mouth of said bottle for free reception and centering of a conventional cap disk when dropped on said shoulder, the inner edges of said open pleats being spaced outwardly from said mouth-spanning portion for the free reception of the bead of a milk bottle therebetween to guide the hood member into located position on the bottle when dropped thereon by contact with the inner and outer walls of said bead, said depressed central portion being depressed to a degree sufficient to locate the hood in capping position and to provide additional stock to be drawn outwardly against the wall of the bottle during capping upon movement of said disk downwardly in said mouth-spanning portion with respect to said hood member.

10. The method of making a hood cap for milk bottles having a cap seat which comprises forming a hood member of thin sheet metal foil having a mouth spanning portion including a 5 depressed central portion receivable into the mouth of a bottle, a concentric rim portion having a wall extending upwardly and outwardly from said mouth spanning portion of lesser depth than the distance from the mouth to the cap seat of said bottle, said rim portion having a plurality of ribs extending transversely and spaced annularly thereof extending outwardly from said wall, and a concentric downwardly flared pleated seat portion, seating said hood member loosely on the head of the bottle, dropping a cap disk onto said mouth spanning portion of such size as to firmly engage the interior of the bottle mouth, forcing said cap disk down into the mouth of the bottle to tilt said wall inwardly and move the hood member downward with the wall in seated engagement with the inner surface of the bottle adjacent the mouth, to seat the rim portion against the rim of the bottle and to bring said ribs into overhanging relationship with said disk and continuing to move said cap disk down to thereafter move the disk with respect to the hood member to pull metal from 15 said depressed portion and iron the same against the inner wall of the bottle between the wall and the cap seat, and thereafter compressing said skirt portion around the bead of the bottle.

RUDOLPH SONNENBERG.
